[57] CLAIM

The ornamental design for a blood sugar strip, as shown
and described.

DESCRIPTION

FIG. 1 is a perspective view of a blood sugar strip
showing my new design;

FIG. 2 is a front elevational view thereof, the rear elevational
view being identical thereof;

FIG. 3 is a top plan view thereof;

FIG. 4 is a bottom plan view thereof;

FIG. 5 is a left side elevational view thereof;

FIG. 6 is a right side elevational view thereof; and,

FIG. 7 is a cross-sectional view thereof, taken along line
VII—VII of FIG. 3.

FIG. 1

FIG. 2

FIG. 3
